AUSTIN FREDK. JACKSON, OF TAUNTON, MASSACHUSETTS, ASSIGNOR TO
REED & BARTON, OF SAME PLACE.

BOTTLE-HOLDER.

SPECIFICATION forming part of Letters Patent No. 367,208, dated July 26, 1887.

Application filed February 25, 1887. Serial No. 228,909. (No model.)

To all whom it may concern:

Be it known that I, AUSTIN FREDERICK JACKSON, a subject of the Queen of Great Britain, at present residing in Taunton, Bristol county, Massachusetts, United States of America, have invented a new and useful Improvement in Bottle-Holders, of which the following is a specification:

Holders for wine-bottles have been constructed of a metallic casing formed of two parts hinged together, and also of an integral body and a detachable base.

My invention is an improvement in this particular class of bottle-holders, and is embodied in the construction and combination of parts hereinafter described and claimed.

In the accompanying drawings, Figure 1 is a side view of bottle holder, part being broken out. Fig. 2 is a front view of its lower portion. Fig. 3 is a horizontal section on line xx , Fig. 1, of the holder and bottle therein. Fig. 4 is a perspective view of the detachable base, and Fig. 5 is a plan view of body A of bottle-holder inverted.

The letter A indicates the integral body or main portion of the bottle-casing, B the handle, and C the detachable base or bottom thereof. All these parts are made in suitable metals and plated externally with silver, or other metal which will impart the desired ornamental finish.

The body A conforms to the general shape of a champagne or other wine bottle, and is made integral with the handle B, which is arranged in vertical position and forms an ornamental portion of the complete holder. The body A has a circumferential rib, a , that prevents it entering the cup shaped base C too far. The latter has a similar rib, and is constructed with perforated lugs 1 2, which are located exteriorly contiguous to its edge or rim, and the body A has correspondingly-located pins, 1' 2', which project horizontally in opposite directions and are adapted to enter the holes or sockets in said lugs 1 2. The body-lug 1 is made ornamental in form, and the base of pin 1', on the base C, corresponds, so that when brought together they have the appearance of a single symmetrical ornament affixed to the front side of the holder. In brief, the essential thing is that the said lug and pin shall have such con-

struction as will not detract from the ornamental appearance of the holder. The ribs a also conceal the joint between the parts A C, and hence the holder presents exteriorly a far more ornamental appearance than others of its class. It is also much stronger and more durable, owing to the body being made solid or integral, and also integral with the handle. The joint-fastenings are, moreover, strong, while at the same time simple in construction.

In practical use the bottle of wine to be served at table, having been previously cooled to the desired degree, is inserted in the integral body portion A of the holder, and the base C applied and locked thereto, as shown in Figs. 1, 2, and 3—that is to say, the bottle is first inserted in the body portion A, and then the base C is applied so that the ribs a meet, the lugs 1 and 2 and pins 1' and 2' being of course separated or not in contact, as shown in dotted lines, Fig. 3. The base C is next turned to the left, as shown by arrow, Fig. 3, to bring the pins 1' and 2' into engagement with the socket or lugs 1 and 2, as shown in full lines, Figs. 1, 3. The pin 3, secured by chain 4, is then inserted in the hole in pin 2', thus locking the two parts of the bottle-holder together and securing the bottle therein.

To release the bottle, it is obviously only necessary to remove the spring-pin and then turn the base C to the left, thereby drawing the pins 1' 2' out of the sockets in lugs 1 2. Both the body A and base C are lined with flannel or some other soft material, which not only serves to cushion the casing, so as to prevent rattling of the bottle within it when the holder is in use, but serves also as a non-conductor of heat, so that the contents of the bottle confined in the holder are kept cool for a long time.

What I claim is—

The improved article of manufacture, consisting of the bottle-holder formed of the bottle shaped body A, having pins 1' and 2', projecting horizontally in opposite directions, and the detachable cup-like base C, having the perforated lugs or sockets 1 and 2, all as shown and described.

AUSTIN FREDK. JACKSON.
